Primary Examiner — Randall H Gholson(74) *Attorney, Agent, or Firm* — Banner & Witcoff, Ltd.(57) **CLAIM**

The ornamental design for a headset with visor, as shown and described.

DESCRIPTION

FIG. 1 is a top front perspective view of a headset with visor showing our new design;

FIG. 2 is a top rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The even-length broken lines depicting of the remainder of the headset with visor show features that form no part of the claimed design. The uneven-length broken lines adjacent to the shaded region form an unclaimed boundary of the design and form no part thereof.

1 Claim, 8 Drawing Sheets**US D872,082 S**
